UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

INSULATING-TUBE MACHINE.

1,137,833.

Specification of Letters Patent. Patented May 4, 1915.

Application filed August 7, 1911. Serial No. 642,875.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Insulating-Tube Machines, of which the following is a specification.

My invention relates to machines for manufacturing tubes or hollow cylinders by a winding process, and it has special reference to such machines as are adapted to produce insulating tubes of relatively large diameters.

The object of my invention is to provide a machine of the class above indicated which shall be readily adjustable for producing very hard insulating tubes of widely varying diameters.

In Patents Nos. 858,383 and 858,384, granted July 2, 1907, to the Westinghouse Electric & Manufacturing Company, on applications filed by Emil Haefely, are shown and described machines which are adapted to produce particularly excellent insulating tubes. The insulating structures which are usually composed of paper, mica and shellac, or some other suitable binder, are suitably built up during the tube-forming process. The process consists in winding a number of convolutions of suitable fabric closely about a mandrel, which forms a part of the machine, having the size and shape desired for the opening in the tube, heat and pressure being applied as the convolutions of insulation are wrapped upon the mandrel in order to fuse the layers or convolutions together and make a solid and durable structure.

According to my present invention, I provide a machine which is adapted for the same process or similar processes of manufacturing insulating tubes as that set forth in the patents above referred to, but, instead of providing a mandrel corresponding in size to the opening of the tube, I provide a large number of guide rolls in addition to a pair of pressure rolls and make these parts radially adjustable relative to a common axis in order to adapt the machine to the manufacture of large tubes of widely varying diameters.

It will be readily understood that large tubes possessing great mechanical strength and high insulating qualities, are particu-

larly useful in the manufacture of core type 55 transformers and various other electric apparatus. By the use of my invention, I am able to make a large number of different sizes of tubes by means of a single machine instead of employing a large number of 60 machines.

Figure 1 of the accompanying drawings, is a sectional elevation, in a longitudinal plane, of a machine constructed in accordance with my invention. Fig. 2 is an end 65 elevation, looking in the direction of arrow *a* of Fig. 1. Fig. 3 is a sectional view on the line III—III of Fig. 1, looking in the direction of arrow *b*, and Fig. 4 is an end elevation, looking in the direction of the arrow *c* 70 of Fig. 1. Figs. 5, 6 and 7 are detail views of the driving connections for the rolls, and Fig. 8 is a plan view of the entire machine.

Referring to the drawings, the structure here shown comprises a stationary base or 75 bed plate 1, to which standards or bearing brackets 2 and 3 are secured, a central adjusting shaft 4, a stationary quill 5, surrounding the shaft and secured to the bracket 2, a pair of cooperating adjustable 80 pressure rolls 6 and 7, electric driving motor 8, a plurality of adjustable guide rolls 9 and suitable gearing.

The adjusting shaft 4 is supported, at one end, in a bearing 10 which is provided 85 in the bracket 2 and, at its opposite end, in a bearing 11 provided in the outer end of the quill 5. The shaft is provided with a pair of beveled gear wheels 12 and 13 and may be rotatively adjusted by means of a hand 90 wheel 14.

The bracket 2 is provided with an annular projection 15, to which the quill 5 is secured by bolts 16, and an annular projection 17 which are concentric with the shaft 4 and 95 are of materially different diameters, the projection 15 being comparatively near the shaft 4. A plurality of radial adjusting screws 18 are rotatively supported, in substantially the same plane, in bearings provided in the projections 15 and 17 and each of them is provided, at its inner end, with a beveled pinion 19 which meshes with the beveled gear wheel 12 on the shaft 4.

At the outer end of the quill 5, a ring or 105 bearing support 20 is held concentric with the shaft 4 by means of spokes or arms 21 and is provided with a plurality of out-

wardly extending, hollow, radial, projections 22 in which internally threaded quills or sleeves 23 are rotatively mounted. The sleeves 23 extend through suitable holes in 5 the ring 20 and teeth are cut at their inner ends to constitute beveled pinions 24 which coöperate with the beveled gear wheel 13. A plurality of screw-threaded rods or adjusting screws 25 are screwed into the outer 10 ends of the sleeves 23 and support bearing blocks 26 at their outer ends.

A plurality of bearing blocks or nuts 27 are screwed onto the adjusting screws 18 so that, as the screws are rotated, the bearing 15 blocks or nuts are adjusted toward the axis of the shaft 4 or away from it. The bearing blocks 26 are similarly adjusted when the sleeves 23 are rotated, by reason of the screw-threaded relation between the screws 20 25 and the sleeves 23.

Since the adjusting screws 18 are all geared to the shaft 4 by means of the gear wheel 12 and pinions 19, and since the sleeves 23 are similarly connected to the 25 shaft 4 by gear wheel 13 and pinions 24, a rotative adjustment of the shaft 4 produces a concurrent adjustment of the bearing blocks 26 and the bearing blocks 27. The gear ratios and the pitch of the screw- 30 threads are so determined as to make the adjustment of the two sets of blocks 26 and 27 not only concurrent but also equal in degree.

The guide rolls 9 are rotatively supported in the bearing blocks 26 and 27 and are preferably uniformly spaced about the center of the shaft 4 at equal distances therefrom so that their outer surface lines constitute spaced lines of a cylindrical surface, as shown in Figs. 2 and 3 of the drawings, except that the pressure roll 7 is substituted in 40 position for one of the guide rolls. The pressure roll 7 is supported in bearing blocks 26^a and 27^a which correspond to the blocks 26 and 27 of the guide rolls and are similar 45 to them except that the block 27^a is provided with a lug 28 which projects upwardly and laterally from it and constitutes a bearing for a short shaft 29.

The pressure roll 6, which coöperates with 50 the roll 7, is rotatively supported in bearing blocks 30 and 31 which are yieldingly mounted on a cross piece 32. The cross piece 32 is adjustably supported between the brackets 2 and 3 by means of adjusting 55 screws 33 and 34 which are nonrotatively secured to the cross piece 32 at their lower ends and pass freely through suitable holes in a stationary cross beam 35 into bevel gear nuts 38 and 39. The nuts are prevented 60 from riding up on the bolts by brackets 36 and 37 and are driven by bevel gears 40 and 41. The gears 40 and 41 are driven synchronously by any suitable means, such as a hand wheel 42, to which they are connected, 65 through gears 43 and 44, shaft 45, beveled

gears 46 and a shaft 47, the two gears 43 being tied together by a shaft 48.

In order to support the screws 25 when the machine is in operation, I provide a series of adjustable rods 49 which are screw-threaded through a ring or annular projection 50 of the stationary bracket 3, the inner ends of which rods are tapered like the dead center of a lathe and engage conical recesses 51 in the outer ends of the screws 25. The 75 arrangement of parts is such that, after the guide rolls 9 are adjusted to the desired positions, the rods 49 are moved into engagement with the ends of the screws 25 where they will remain during the operation 80 of the machine.

The roll 7 is driven by the electric motor 8 through any suitable gearing, the arrangement illustrated in the drawings comprising a sprocket wheel 52 mounted on a short 85 shaft 74 and geared to the shaft of the motor 8, a sprocket wheel 53 rotatably supported on a projection 54 of the bracket 2, a chain 55 connecting the two sprocket wheels and an intermediate sprocket wheel 90 56 which is mounted on the outer end of shaft 29 and operates equally well at any point between the sprocket wheels 52 and 54, thereby permitting the roll 7 to be driven in any position to which it may be adjusted. 95 The roll 6 may be similarly driven by means of a pair of spaced sprocket wheels 57 and 58 which are respectively mounted on shaft 59 and projection 60 and are connected by a chain 61, the sprocket wheel 58 being so 100 geared to the motor shaft as to produce the proper rotation of the roll 6 relative to the roll 7. The bearing block 30 of the roll 6 is provided with a projection 62 in which a short shaft 63, corresponding to the shaft 29, 105 is supported and is geared to the roll 6 at one end and is provided with a sprocket wheel 64 at the opposite end which is located between the sprocket wheels 57 and 58 and is driven by the chain 61.

The operation of the machine is as follows: The guide rolls 9 and the pressure roll 7 are adjusted to correspond to the inside diameter of the insulating tube which it is desired to produce by suitably rotating the 115 hand wheel 14. The correct position may be accurately determined by cutting a strip of flexible card-board or other similar material to a length corresponding to the desired inside circumference of the tube to be 120 deformed, wrapping it about the rolls of the machine and adjusting the rolls until the ends of the strip just meet.

In order to produce a perfectly cylindrical surface, I prefer to wrap a templet of sheet 125 metal or stiff cardboard about the rolls after they are adjusted and before the winding of the tube is commenced.

After the guide rolls and the roll 7 are set, the rods 49 are set in position to support 130

the outer ends of the screws 25 and the roll 6 is lowered into contact with the roll 7 by adjusting the hand wheel 42. Thin paper, or other suitable fabric of a width corresponding to the desired length of tube, is then fed through the pressure rolls 6 and 7 and is wrapped around the guide rolls 9. After one convolution of the paper, or other fabric, is wound upon the rolls, the motor is operated at full speed and the paper or other fabric is wound into a tube, the process being continued until the desired thickness of tube is secured. As the paper or other fabric is fed into the machine, shellac, or other suitable binder, is applied by a brush or otherwise, in order to produce a very solid insulating tube.

Instead of applying the binder in the form of a liquid, the fabric of which the tube is built may be previously prepared for the purpose and adapted, under heat and pressure, to fuse the layers or convolutions of the tube together and make a solid, durable structure.

Since the roll 6 is yieldingly supported, the bearing blocks 30 and 31, being provided with projections 65 and 66, which extend loosely through suitable holes in the cross member 32, and springs 67 and 68 being interposed between the bearing blocks and the cross member, the pressure between the rolls may be adjusted merely by turning the hand wheel 42.

In order to heat the tube during the process of manufacture, the roll 7 is provided with an electric heater 69, the terminals of which are brought out through collector rings 70 and stationary brushes 71 which are connected to external circuit conductors 72 and 73. Both of the rolls may be heated, if desired.

When the tube is completed, the roll 6 is moved away from the roll 7 and the hand wheel 14 is rotated to move the rolls 9 and the pressure roll 7 inwardly. This action separates the screws 25 from the stationary supporting rods 49 and permits the tube to be removed at the opposite end of the machine from the motor 8, the conductors 72 and 73 being detached from the heating conductor 69 in order to permit of such removal.

The machine illustrated may, of course, be utilized for any suitable purpose, and its structure may be modified in detail, without departing from the spirit of my invention. Consequently, I desire that only such limitations shall be imposed as are indicated in the appended claims.

I claim as my invention:

1. A tube machine comprising a plurality of guide rolls disposed in the form of a hollow cylinder, a pair of coöperating pressure rolls having their engaging surfaces in the periphery of the cylinder to which the outermost lines of said guide rolls belong,

and means for radially and concurrently adjusting the positions of the guide rolls and one of the pressure rolls.

2. A tube machine comprising a plurality of guide rolls disposed in the form of a hollow cylinder, a pair of coöperating pressure rolls having their axes in a radial plane and their engaging surfaces in the periphery of the cylinder to which the outermost lines of said guide rolls belong, and radially adjustable means for supporting the ends of the guide rolls and one of the pressure rolls. 75

3. A tube machine comprising a plurality of guide rolls disposed in the form of a hollow cylinder, a pair of coöperating pressure rolls having their engaging surfaces in the periphery of the cylinder to which the outermost lines of said guide rolls belong, means for oppositely driving the pressure rolls, and means for radially and concurrently adjusting the positions of the guide rolls and one of the pressure rolls. 85

4. A tube machine comprising a plurality of guide rolls disposed in the form of a hollow cylinder, a pair of coöperating pressure rolls having their engaging surfaces in the periphery of the cylinder to which the outermost lines of said guide rolls belong, means for radially and concurrently adjusting one of the pressure rolls and the guide rolls, and independent means for adjusting the position of the other pressure roll. 95

5. A tube machine comprising a base and a stationary bracket or pedestal secured thereto, a substantially horizontal adjusting shaft rotatably supported by the pedestal, a stationary quill or sleeve surrounding the shaft and secured to the pedestal, a plurality of radial screws rotatably supported in a plane substantially perpendicular to the center of the shaft, a second set of adjusting screws similarly supported in a parallel plane, interposed gearing between the screws and the adjusting shaft, and a plurality of rolls so supported by the radial screws that an adjustment of the shaft effects concurrent adjustment of the rolls. 105

6. A tube machine comprising a base, a stationary bracket or pedestal secured thereto, a substantially horizontal adjusting shaft rotatably supported by the pedestal, a stationary quill or sleeve surrounding the shaft and secured to the pedestal, a plurality of radial screws rotatably supported at the inner end of the sleeve or quill in a plane substantially perpendicular to the shaft, a second set of radial screws similarly supported at the outer end of the sleeve or quill, a plurality of bearing blocks supported by the radial screws, rolls rotatably supported in the bearing blocks and substantially parallel to the shaft, and means operated by the adjusting shaft for concurrently rotating the radial screws. 115

7. A tube machine comprising a base, a stationary bracket or pedestal secured thereto, a substantially horizontal adjusting shaft rotatably supported by the pedestal, a stationary quill or sleeve surrounding the shaft and secured to the pedestal, a plurality of radial screws rotatably supported at the inner end of the sleeve or quill in a plane substantially perpendicular to the shaft, a second set of radial screws similarly supported at the outer end of the sleeve or quill, a plurality of bearing blocks supported by the radial screws, guide rolls rotatably supported in the bearing blocks in the form of a hollow cylinder concentric with the adjusting shaft, a pressure roll corresponding in mounting and adjustment to the guide rolls, and a second pressure roll coöperating with the first. 50
- 10 8. A tube machine comprising a base, a stationary bracket or pedestal secured thereto, a substantially horizontal adjusting shaft rotatably supported by the pedestal, a stationary quill or sleeve surrounding the shaft and secured to the pedestal, a plurality of radial screws rotatably supported at the inner end of the sleeve or quill in a plane substantially perpendicular to the shaft, a second set of radial screws similarly supported at the outer end of the sleeve or quill, a plurality of bearing blocks supported by the radial screws, guide rolls rotatably supported in the bearing blocks in the form of a hollow cylinder concentric with the adjusting shaft, a pressure roll corresponding in mounting and adjustment to the guide rolls, and a second pressure roll coöperating with the first. 55
- 15 9. A tube machine comprising a base, a stationary bracket or pedestal secured thereto, a substantially horizontal adjusting shaft rotatably supported by the pedestal, a stationary quill or sleeve surrounding the shaft and secured to the pedestal, a plurality of radial screws rotatably supported at the inner end of the sleeve or quill in a plane substantially perpendicular to the shaft, a second set of radial screws similarly supported at the outer end of the sleeve or quill, a plurality of bearing blocks supported by the radial screws, guide rolls rotatably supported in the bearing blocks in the form of a hollow cylinder concentric with the adjusting shaft, a pressure roll corresponding in mounting and adjustment to the guide rolls, and a second pressure roll coöperating with the first. 60
- 20 10. A machine comprising a plurality of guide members disposed in the form of a hollow prism and together adapted to constitute a winding core, and radially adjustable coöperating pressure members having their engaging surfaces in the outer periphery of the prism. 65
- 25 11. A machine comprising a plurality of guide members disposed in the form of a hollow prism and together adapted to constitute a winding core, and independently adjustable and coöperating pressure rolls having their axes in a radial plane and their engaging surfaces in the outer periphery of the prism. 70
- 30 12. A tube machine comprising a plurality of guide rolls disposed in the form of a hollow cylinder and together adapted to constitute a winding core, and a pair of positively driven coöperating pressure members having their engaging surfaces in the outer periphery of the cylinder. 75
- 35 13. A tube machine comprising a plurality of guide rolls disposed in the form of a hollow cylinder, a pair of coöperating pressure members having their engaging surfaces in the periphery of the cylinder and means for radially and concurrently adjusting the positions of the rolls and the pressure members. 80
- 40 14. In testimony whereof, I have hereunto subscribed my name this 31st day of July, 1911. 85
